MANUFACTURE OF PIPES AND THE LIKE
FROM SHEET METALWalter Reginald Hume, Melbourne, Victoria,
Australia, assignor to Hume Steel Limited,
Melbourne, Victoria, AustraliaApplication May 26, 1934, Serial No. 727,812
In Australia June 15, 1933

6 Claims. (Cl. 153—54)

This invention relates to the manufacture of sheet metal pipes and like hollow bodies wherein flat metal plate is caused to travel lengthwise between successive sets of shaping rollers which progressively bend the plate from its longitudinal edges towards its center so that the plate converges from the flat at one end into tubular form at the other end.

In prior proposals of this kind, some or all of the sets of shaping rollers consist of an upper roller and a lower roller, both rotatable about horizontal axes and extending across the longitudinal center line of the plate, the respective rollers having complementary convex-concave peripheral faces which engage the upper and lower surfaces of the plate. Owing to the rollers extending across the center line of the plate as aforesaid, the longitudinally extending central zone of the plate is, from the time the plate enters between the first rollers until it assumes or approaches the desired tubular condition, continuously subject to bending or to pressure by the various pairs of rollers. This bending or pressure, which is additional to the bending or pressure that is actually necessary for imparting the desired finished curvature to the plate, considerably increases friction between the plate and rollers as well as wear on the rollers and may result in the central longitudinal zone of the plate, while flat, being compressed to an extent sufficient to disaffect the subsequent bending of the central zone or cause the finished pipe to lose its true circular section or cylindrical shape.

The present invention provides an improved method of manufacturing sheet metal pipes and like hollow bodies according to which a plate while moving lengthwise is subjected at each side of its longitudinal center line, but not at or across such center line, to pressure between sets of shaping rollers whereby portions of the plate at opposite sides of the center line are progressively bent towards each other in arcuate form until the longitudinal edges thereof meet, the radii of all of the bends being the same as the radius of the pipe to be formed, so that subsequent bending actions merely extend or continue the curvature of previously curved portions without subjecting said portions to further bending or pressing actions, while a flat longitudinally extending central portion of the plate of generally isosceles triangular shape which gradually diminishes in area as bending operations proceed remains unsubjected to pressure or bending until the apex or leading end thereof is adjacent the final set of rollers. The fact that the longitudinal

central zone of the plate remains flat and unsubjected to pressure as aforesaid tends to keep the work perfectly straight during bending operations so that a substantially perfectly straight tube results.

The invention also provides apparatus for carrying the method into effect and comprising sets of shaping rollers between which the plate is caused to pass, arranged at intervals in the direction of travel of the plate, some of the rollers of each set being located at one side and the other rollers at the opposite side of the longitudinal center line of the plate, each set of rollers comprising two lower or outside rollers adapted to rotate about vertical axes and having peripheries of concave curvature conforming to the external curvature of the pipe to be formed, and two cooperating upper or inside rollers adapted to rotate about a transverse axis and having peripheries of convex curvature conforming to the internal curvature of the pipe to be formed, each succeeding set of rollers being disposed nearer to the longitudinal center line of the plate than the preceding set so that the plate is progressively bent from its longitudinal edges towards the center thereof into tubular form.

According to a preferred mode of carrying out the method, a plate in a substantially flat condition is fed to and caused to travel longitudinally between sets of shaping rollers arranged at intervals in the direction of travel of the plate, some of the rollers of each set being located at one side, and the other rollers at the opposite side, of the longitudinal centre line of the plate. The first group or set of shaping rollers act upon the longitudinal edge portions of the plate to bend these portions arcuately in conformity with the curvature of the finished pipe or like body. Each succeeding set of rollers is disposed nearer to the longitudinal centre line of the plate than the preceding series of rollers and act upon the plate in a similar manner so that its longitudinal edge portions are gradually or progressively bent into semi-circular form and their longitudinal edges abutted ready for welding together. The plate is fed forwardly by the shaping rollers.

The invention permits of the economic production of pipes which are practically perfectly straight and cylindrical and of relatively great length devoid of circumferential joints.

The invention also involves apparatus for carrying out the manufacture of pipes by the improved method.

Referring to the drawings which form part of this specification—

Figure 1 is a side elevation of a machine according to one embodiment of the invention.

Figure 2 is a plan of Figure 1.

Figure 3 is an end elevation looking on the 5 left hand end of Figure 1.

Figure 4 is a perspective view illustrating the manner of bending the plate into tubular form.

Figure 5 is a fragmentary end view on an enlarged scale of one of a set of shaping rollers, 10 and associated parts of the machine.

Figure 6 is a part sectional view taken on line VI—VI of Figure 5.

Figure 7 is a fragmentary end view of a further set of shaping rollers and associated parts.

15 Figure 8 is a side elevation of the final two sets of shaping rollers and associated parts.

Figure 9 is an end view of the sets of rollers and associated parts seen in the left hand portion side of Figure 8.

20 Figure 10 is an end view of the final set of rollers and associated parts seen in the right hand portion of Figure 8.

Figure 11 is a detail view partly in section showing a bar and a backing member which extend within the shaped metal sheet adjacent the final shaping rollers in order to assist the welding of the abutted longitudinal edges of the sheet.

25 Figure 12 is an end view looking on the right hand end of Figure 11.

Figure 13 is an enlarged plan view of a lower portion of the backing member seen in Figures 11 and 12 showing arrangements for the water cooling thereof.

30 Figure 14 is a vertical cross section taken through the centre of the backing member.

In order to more readily explain the method, reference is made to Figure 4 which depicts a plate 2 in an intermediate stage of the bending operations. It will be seen therefrom that the trailing end 2a is in its original flat condition, while the opposed longitudinal edge portions 2b are progressively bent in curved formation, the radii of the bends being uniform and equal to 40 the radius of the pipe to be formed, while the extent of the bends increases towards the leading end 2c which, at the stage indicated, is shaped into cylindrical form. It will also be noted that the central portion of the plate remains 45 substantially flat until the plate has assumed the desired cylindrical form. Such flat portion will be of generally isosceles triangular shape having the trailing edge 2a as its base and its sides, indicated by the references 2d, defined by lines from which the longitudinal edge portions 2b commence to curve upwardly from the flat portion by the action of the successive sets of rollers. The approximately triangular flat portion will gradually diminish in area as the 50 bending operations proceed and will disappear just prior to the entire plate arriving at a tubular condition.

55 Referring now more particularly to Figures 1, 2 and 3, the apparatus is shown as including eight sets of shaping rollers, the various sets being denoted generally in Figure 1 by the reference characters A, B, C, D, E, F, G, H. The plate 2 to be shaped travels in the direction from the "A" set of rollers to the "H" set so that it is progressively acted upon by each succeeding set 60 of rollers.

70 The rollers of set "A" comprise two lower or outside rollers 3 rotating about vertical spindles 4 disposed at opposite sides of the longitudinal centre line of the apparatus which is coincident

with the longitudinal centre line of the plate 2. The periphery of each horizontally rotating outside roller 3 is of concave curvature and of approximately quarter-circular profile, conforming to the external curvature of the pipe to be formed. Cooperating with the pair of rollers 3 is a pair of upper or inside rollers 6 mounted upon a transverse spindle 7. The periphery of each roller 6 is of convex curvature conforming to the internal curvature of the pipe to be formed. Thus, as the plate 2 is entered and passed between the cooperating pairs of rollers 3, 6, the longitudinal edge portions of the leading end of the plate are initially bent into the desired curved form, the radius of the bends being 15 the same as the radius of the pipe to be formed, while the central portion of the plate remains flat.

20 The rollers of sets B, C, D, E and F may be substantially identical with those of set A and are indicated by like numerals. The rollers of each successive set are, however, arranged closer to the longitudinal centre line of the apparatus as will be seen in Figure 2 so that the plate will be gradually shaped into cylindrical form while 25 passing between the sets of rollers.

25 The vertical spindles 4 of the various outside rollers and the transverse spindles 7 of the upper or inside rollers 6 may be supported by bearing brackets 8 secured to a framework 9. The outside rollers may be driven from a main shaft 11 through spur gearing 12, a countershaft 13, bevel gearing 14, transverse shafts 15, worms 16 and wormwheels 17. The inside rollers 6 of sets A and B may be positively driven as by being 30 bevel geared as at 5 to the respective side rollers 3, but such inside rollers as well as those of sets C, D, E and F may, if desired, be devoid of positive driving means and rotate merely by friction with the plate.

35 The wormwheels 17 may be made fast to the respective outside rollers 3, as by means of pegs 18 extending within co-aligned apertured bosses 19 of the wormwheels 17, and rollers 3, as seen in Figures 5 and 6 which may be assumed to illustrate the E set of rollers. It will also be seen from these two figures that the transverse shafts 15 are supported by bearing brackets 21 attached to the brackets 8 before referred to.

40 According to Figure 7, which illustrates the F set of rollers, the two inside rollers 6 are canted or tilted upwardly towards each other, the shaft 7 having oppositely inclined portions 7a for the respective rollers.

45 The rollers of set G (see the left hand part of Figure 8 and Figure 9) comprise outside rollers 3a and inside rollers 6a similar to those of the preceding set but, as at this stage the plate is closely approaching the desired cylindrical form, the inside rollers are of comparatively small diameter to avoid them fouling the upper parts of the curved plate. For similar reasons, the inside rollers are mounted upon a comparatively short shaft 22 supported by a hanger 23 depending from an overhead frame member 24.

50 The rollers of set H (i. e. the final set as seen in the right hand part of Figure 8 and in Figure 10) comprise two laterally spaced outside rollers 3b having concave peripheries of substantially semi-circular profile, the upper and lower rims 3c of the two rollers contacting with, or being in close proximity to, each other in alignment with the longitudinal centre line of the apparatus, thus defining a substantially circular passage or orifice 26 (Figure 12) conforming to the external 55

5 contour of the pipe to be formed. The co-operating inside rollers 6b are located within the confines of this passage or orifice and are of relatively small diameter and may be canted or tilted upwardly away from each other as seen in Figures 10 and 12. These rollers may be supported by an extension 23a of the hanger 23 which supports the rollers 6a of set G. The hanger and frame may be reinforced by stays 25 (Figure 8).

10 The aforesaid orifice or passage furnished by the rollers 3b of set H is preferably not truly circular but of slightly greater diameter measured horizontally than vertically so that the plate 2 in passing between the rollers is slightly elliptical. 15 As soon as the plate passes the two rollers, however, the resilience of the plate causes it to assume a substantially truly cylindrical form as indicated in Figure 12.

15 The vertical spindles 4a of the outside rollers 20 3a, 3b may be supported by bearing brackets 8a secured to the framework 9 and driving connections similar to those referred to in connection with the preceding set of rollers may extend from countershaft 13 to worm wheels 17 associated 25 with the outside rollers.

It will be evident from the foregoing that, as the trailing end of the plate is entering between and being acted upon by the rollers of set A, the forward or leading end portion of the plate 30 has assumed a substantially cylindrical form. Thus, the plate converges from the flat at one end to a tubular form at the other end with the side edges curved upwardly to a progressively greater extent from the flat to the tubular end. 35 This procedure and formation which results in the central portion of the plate remaining flat until the plate assumes cylindrical form ensures that the pipe will be practically perfectly straight from end to end.

40 In order to prevent any possibility of the central flat portion of the plate sagging due to roller pressure during the bending process, a bearer 10 may extend lengthwise beneath the centre portion of the plate so as to contact with the under surface thereof as in Figures 5, 7, 9 and 10.

The longitudinal meeting edges of the plate 2 may be progressively welded together soon after they emerge from the orifice or passage 26 provided by rollers 3b. In order to assist effective 50 welding, a backing member 26 may be arranged to bear upwardly against the internal surface of the now cylindrical plate in vertical alignment with the welding electrode 27. The backing member, which may be of copper in order to 55 exercise a desirable chilling effect upon the line of weld, may have a depending stem 28 engaged at its lower end by a spring 29 anchored to an upper bar 30 attached at its front end to the rear of the hanger 23. A lower bar 31 may also be 60 attached at its front end to the hanger and secured at its rear end to the upper bar by straps 32. The backing member may be provided at its front with an anti-wearing piece such as a steel nose 33.

65 Provision may be made for cooling the backing member by suitable fluid. For example, the backing member and a separable base 34 therefor may be provided in their contiguous faces with grooves 35, 36 defining a passage 37 for water or 70 the like which may be circulated through the passage from a supply pipe 38 to a discharge pipe 39. A gasket 40 may extend between the backing member and its base to prevent leakage of fluid from the passage.

75 In the case of manufacturing comparatively

small diameter pipes, say up to six or eight inches in diameter, there is a possibility that, owing to shrinkage or contraction taking place during the cooling of the welded joint, the resultant pipe 5 may lose its desirable straightness and become slightly curved, in a longitudinal direction, the curvature being concave along the line of the weld. To counteract any such tendency, the bed of the machine may be "roached" or alternatively, the sets of rollers commencing from set 10 B may be successively arranged at a slightly lower level than each preceding set of rollers, so that the plate is fed forwardly at a slight downward inclination or curvature which is corrected 15 or compensated for by shrinkage or contraction which occurs during the cooling of the weld.

In some instances, it may be preferable to isolate or separate the final set of rollers H from the other set of rollers so that the plate may be first shaped into partially cylindrical form by sets A 20 to G, then removed and passed through the set H which may, with the appropriate welding plant, form a separate unit.

To permit of the production of pipes of different diameters, the brackets 8, 8a supporting the 25 spindles of rollers 3, 3a, 3b and 6, 6a, 6b may be adjustable in a lateral direction upon the frame 9. Alternatively, the brackets may be mounted upon longitudinally extending beams or frame members which may be swung or adjusted towards and from each other so that the lateral spacing of the rollers may be varied to suit the diameter of the pipes to be formed. The rollers 30 may be readily removed from their spindles and replaced by other rollers having peripheries of 35 the requisite contour.

Having now described my invention, what I claim as new and desire to secure by Letters Patent is:—

1. Apparatus for manufacturing pipes and like hollow bodies from flat metal plate; comprising sets of shaping rollers, between which the plate is caused to pass, arranged at intervals in the direction of travel of the plate, some of the rollers of each set being located at one side and the other rollers at the opposite side of the longitudinal centre line of the plate, each succeeding set of rollers being disposed nearer to the longitudinal centre line of the plate than the preceding set so that the plate is progressively bent 45 from its longitudinal edges towards the centre thereof into tubular form, the final set of rollers comprising two outside rollers adapted to rotate about vertical axes and having peripheries of concave semi-circular profile defining between them 50 an orifice conforming substantially to the external circular form of the pipe to be produced, and two co-operating inside rollers disposed within said orifice or passage on opposite sides of the longitudinal center line of the plate and adapted to rotate about different axes which extend transversely relatively to the path of travel of the plate, the peripheries of the inside rollers being 55 of convex curvature conforming to the internal curvature of the pipe to be formed.

2. Apparatus according to claim 1; in which the diameter of the orifice or passage defined by said outside rollers of the final set of rollers is slightly greater measured in one direction than in a direction at right angles thereto so that the 70 plate may assume a slightly elliptical form in passing between said rollers and after emerging therefrom may automatically assume a substantially true circular form.

3. Apparatus for manufacturing pipes and like 75

hollow bodies from flat metal plate, comprising sets of shaping rollers between which the plate is caused to pass, arranged at intervals in the direction of travel of the plate, some of the rollers of each set being located at one side and the other rollers at the opposite side of the longitudinal center line of the plate, each set of rollers comprising two lower or outside rollers adapted to rotate about vertical axes and having peripheries of concave curvature conforming to the external curvature of the pipe to be formed, and two cooperating upper or inside rollers mounted on opposite sides of the longitudinal center line of the plate and adapted to rotate about different axes which extend transversely relatively to the path of travel of the plate and having peripheries of convex curvature conforming to the internal curvature of the pipe to be formed, each succeeding set of rollers being disposed nearer to the longitudinal center line of the plate than the preceding set so that the plate is progressively bent from its longitudinal edges towards the center thereof into tubular form.

4. An apparatus for manufacturing pipes and like hollow bodies from flat metal plate, comprising a plurality of spaced sets of shaping rollers arranged at intervals in the direction of travel of the plate and through which the plate is progressively caused to pass, the first set of rollers through which said plate is passed having pairs of rollers positioned to engage portions of the plate adjacent the side edges thereof and bend the edges toward each other to form a bend in said portions having a radius of curvature equal to the radius of the pipe to be formed, while leaving the central portion of the plate flat, each successive set of rollers through which the plate is passed having pairs of rollers positioned to engage flat portions of the plate immediately adjacent the bent portions formed by the set of rollers from which the plate has just passed and bend the side edges of the plate closer together to form in said last-mentioned flat portions a bend adjacent to and continuous with the previously-formed bend and having the same radius of curvature, whereby the flat portions of the plate on opposite sides of the longitudinal center line are progressively bent toward each other in arcuate form until the longitudinal side edges meet without bending the previously-bent portions, the final set of rollers comprising two outside rollers adapted to rotate about vertical axes and having peripheries of concave semi-circular profile defining between them an orifice conforming substantially to the external circular form of the pipe to be produced, and each set of rollers including two cooperating inside rollers mounted on opposite sides of the longitudinal center line of a plate fed through the apparatus for rotation about axes which extend transversely relatively to the path of travel of the plate within said orifice and having peripheries conforming to the internal curvature of the pipe to be formed.

5. An apparatus for manufacturing pipes and like hollow bodies from flat metal plate, comprising a plurality of spaced sets of shaping rollers arranged at intervals in the direction of travel of the plate and through which the plate is progressively caused to pass, the first set of rollers through which said plate is passed having pairs of rollers positioned to engage portions of the plate adjacent the side edges thereof and bend the edges toward each other to form a bend in said portions having a radius of curvature equal to the radius of the pipe to be formed, while leaving the central portion of the plate flat, each successive set of rollers through which the plate is passed having pairs of rollers positioned to engage flat portions of the plate immediately adjacent the bent portions formed by the set of rollers from which the plate has just passed and bend the side edges of the plate closer together to form in said last-mentioned flat portions a bend adjacent to and continuous with the previously-formed bend and having the same radius of curvature, whereby the flat portions of the plate on opposite sides of the longitudinal center line are progressively bent toward each other in arcuate form until the longitudinal side edges meet without bending the previously-bent portions, each succeeding set of rollers being arranged at a slightly lower level for imparting a downward curvature to the tube being formed to compensate for warpage due to shrinkage upon welding the side edges of the bent plate together to complete the tube, the final set of rollers comprising two outside rollers adapted to rotate about vertical axes and having peripheries of concave semi-circular profile defining between them an orifice conforming substantially to the external circular form of the pipe to be produced and each set of rollers including two cooperating inside rollers mounted on opposite sides of the longitudinal center line of a plate fed through the apparatus for rotation about axes which extend transversely relatively to the path of travel of the plate within said orifice and having peripheries conforming to the internal curvature of the pipe to be formed.

6. In a roller bending apparatus for producing pipes and like hollow bodies from flat metal plates, a set of shaping rollers comprising two outside rollers adapted to rotate about vertical axes and having peripheries of concave, approximately semi-circular, profile defining between them an orifice having a diameter somewhat greater measured in one direction than in a direction at a right angle thereto, and two cooperating inside rollers mounted on opposite sides of the longitudinal center line of a plate fed through the apparatus for rotation about different axes which extend transversely relatively to the path of travel of said plate within said orifice and having peripheries conforming to the internal curvature of the pipe to be formed.

W. R. HUME.
